UNITED STATES PATENT OFFICE.

GEORGE M. PETTENGILL, OF HAVERHILL, MASSACHUSETTS, ASSIGNOR TO HAMEL SHOE MACHINERY COMPANY, A CORPORATION OF MASSACHUSETTS.

HEEL-NAILING MACHINE.

1,345,876.

Specification of Letters Patent.

Patented July 6, 1920.

Application filed July 30, 1918. Serial No. 247,352.

To all whom it may concern:

Be it known that I, GEORGE M. PETTENGILL, a citizen of the United States, residing at Haverhill, in the county of Essex and 5 State of Massachusetts, have invented certain new and useful Improvements in Heel-Nailing Machines, of which the following is a specification, reference being had therein to the accompanying drawings.

10 This invention relates to heel nailing machines and particularly to that type in which a reciprocatory cross head provided with a rotary turret is employed.

More specifically the present invention 15 comprises improvements particularly adapted for use in connection with that form of heel nailing machine disclosed in the patent to Pettengill, 1,119,763, December 1, 1914, and in which the rotatable turret is held 20 locked in either of two operative positions but is unlocked and turned from one to the other of said positions by the operator. In the above machine the unlocking and locking of the turret is performed manually and 25 in connection with the carrying out of another operation, the present invention not being specifically concerned with this feature of the prior device but relating entirely to means for automatically turning the turret 30 ret after the same has been unlocked.

The invention consists in furnishing the machine with a rotatable turret so arranged that it tends, when unrestrained, to turn to one of its operative positions, combined with 35 automatically operating devices for moving the turret to another of its operative positions.

The invention also consists in providing resiliently acting means for turning the turret in one direction, means for returning it, and power actuated means for resetting said resilient means preparatory to a second actuation of the turret thereby.

Another feature of the invention consists 45 in the provision of means automatically acting to disengage the turret turning means from the turret upon completion of the turning operation.

Other and further objects and advantages 50 of the invention together with improved details of construction and combinations of parts will be hereinafter set forth at length in the specification and particularly pointed out in the claims, reference being had to

the annexed drawings as disclosing a preferred embodiment thereof and in which,

Figure 1 is an elevational view of the mechanism constituting the invention as applied to a machine of the class described, so much only of the latter being shown as is necessary for an understanding of the present device, and

Fig. 2 is a plan view of the parts shown in Fig. 1.

1 indicates a portion of the frame of a machine providing a vertical guideway for a rod 2, reciprocable therein, said rod, together with a similar rod upon the opposite side of the machine, and not herein shown, having connected to its upper end a cross head 3. At the central portion of the cross head is a transversely extending rotatable shaft 4, having fixed thereon a turret 5 providing divergent arms 6, 7, said arms being intended for holding the spanker block and the nail-driving holder, respectively. The arm 6 is somewhat longer than the arm 7, as will appear from comparison of the dotted-line position of the latter with the full-lines showing the arm 6 in Fig. 1, 80 the metal provided by the additional length of the arm 6 serving as a weight which tends to turn the turret to the position shown in Fig. 1, it being evident, however, that, if desired, these arms might be made of substantially the same length with a spring of auxiliary weight for swinging the turret in the manner above noted.

85 Fixed upon the forwardly extending end of the shaft 4 and outside the forward surface of the cross head 3, is a flange 8, said flange being provided with a pair of spaced apart notches 9 and 10 with which a spring-pressed, slidable bolt 11 is adapted to have locking engagement, the relation of said notches 9 and 10 being such that engagement of the bolt 11 therewith serves to hold the turret fixed with relation to the cross head in proper position for employment of either the spanking or nail-driving devices. 100 The mechanism as hereinbefore described is all old and well known in the patent to Pettengill, above noted, to which patent reference may be had for a fuller disclosure of the same.

105 At a point substantially diametrically opposite the notches 9 and 10, the flange 8 is provided with an elongated slot 12 forming

a shoulder at 13. Projecting outwardly from the forward face of the cross head at 14 is a pivot pin or bolt upon which is swingingly mounted a lever 15, one end 16 of which extends in the direction of the turret and has pivoted upon its extremity by means of a pin 17, a pawl 18. The pawl 18 has a downwardly projecting arm 19 to which is connected one end of a tension spring 20, the other end thereof being connected to a pin 21 fixed within the lever arm 16. The pawl 18 has its free extremity provided with a square shoulder 22, arranged for engagement with the shoulder 13 of the notch 12, and is further provided with an inclined cam surface 23.

24 is an eccentric roll mounted upon a pin 25 projecting forwardly from the face of the cross head, said roll lying in the path 20 of movement of said cam surface 23 and serving upon contact of the latter therewith to move said pawl outwardly away from the flange 8, whereby to disengage said shoulders 22 and 13. 26 is a coiled tension 25 spring connected at one end to a pin 27 fast in the lever arm 16, and at its opposite end to an eye formed in the extremity of a screw 29 adjustable in a bracket 30 carried upon the cross head by means of a nut 31 having 30 engagement with the upper end of said screw. The lever 15 is provided with an arm 32 extending oppositely to the arm 16, said arm 32 lying in the vertical plane of a roll 33 pivotally supported upon the upper extremity of a bracket 34 carried by the frame member 1.

The operation of the device is as follows, it being understood that as shown in Fig. 1 the machine is illustrated with the parts in 40 the position in which they are left at the end of the up-stroke of the cross head following the spanking stroke thereof, the bolt 11 engaging within the notch 10 still holding the turret in fixed position, and the 45 shoulder 22 of the pawl 18 being in engagement with the shoulder 13 of the notch 12, thereby holding the lever arm 16 in downwardly inclined position with the spring 26 under tension. The operator now releases 50 the bolt 11, by mechanism not herein shown, but fully illustrated in the patent above referred to, whereupon the tension of spring 26 acting through lever arm 16, and the pawl 18 acts to turn the turret until the 55 notch 9 is brought opposite the bolt 11, whereupon the latter snaps into the notch 9 holding the turret in position for performing the nailing stroke. During the final portion of the movement of the turret the 60 cam surface 23 engages the eccentric roll 24, thereby disengaging the shoulder 22 from the shoulder 13, thus permitting free turning movement of the turret upon a further retraction of the bolt 11.

65 The cross head now descends to perform

its nailing stroke, and the lever arm 32, which is now in the dotted-line position shown in Fig. 1, contacts with the roll 33 and is thereby swung into the position shown in Fig. 1, this, however, being an 70 idle operation. Upon the up-stroke of the cross head, the lever 15 again assumes the position shown by the dotted lines in Fig. 1, the pawl again being thrown outwardly by contact with the eccentric roll 24. The 75 operator now again releases the bolt 11, whereupon the weight of the arm 6 of the turret serves to swing the same downwardly from the dotted-line position, shown at 80 35 in Fig. 1, to the full-line position thereof, the bolt 11 again entering the notch 10 to fix the turret in operative position. The cross head now descends on the spanking stroke, and the lever arm 32 again contacts with the roll 33 swinging the arm 16 down 85 into the full-line position, and at this time the shoulder 22 of the pawl 18 snaps beneath the shoulder 13 of the notch 12 due to the action of the spring 20, thus locking the pawl and the lever 16 in position as shown in 90 Fig. 1, the cross head now returning to its upper position ready to repeat the above cycle of movements.

Having thus described the invention and the mode of operation of the same, what I 95 claim and desire to secure by Letters Patent of the United States is,—

1. In a machine of the class described, a rotatable turret, means for locking said turret in either of a plurality of operative 100 positions, means tending to turn the turret into one of said operative positions when removed therefrom, and automatically acting means for moving said turret to another of its operative positions against the 105 tendency of said first means.

2. In a machine of the class described, an oscillatable turret, means for locking said turret in either of two operative positions, gravity means tending to turn said turret 110 into one of its operative positions, and spring means for moving it to its other operative position.

3. In a machine of the class described, an oscillatable turret, means for locking 115 said turret in either of two operative positions, and resiliently actuated means for turning said turret from one of said positions to the other, said means comprising a pawl and ratchet.

4. In a machine of the class described, an oscillatable turret, locking means for said turret and turning means for the turret, said turning means comprising a ratchet member fast to the turret, a pawl engageable with the ratchet member for turning the same, and resilient means for actuating the pawl.

5. In a machine of the class described, an oscillatable turret, a ratchet fast to the 130

turret, a pawl engageable with said ratchet, means for actuating said pawl to turn the ratchet, and means for disengaging said pawl and ratchet upon completion of the 5 turning movement.

6. In a heel nailing machine, in combination, an oscillatable turret, a ratchet fast to the turret, a pawl carrier, a pawl pivoted thereto, spring means tending to engage said 10 pawl with the ratchet, means for actuating the pawl carrier whereby to turn the ratchet, and cam means for disengaging said pawl from the ratchet upon completion of the turning movement.

7. In a heel nailing machine having a reciprocating cross head, in combination, a turret rotatable upon the cross head, means for locking the turret in either of a plurality of operative positions, a ratchet fast to the 20 turret, a pawl for driving the ratchet to turn said turret in one direction, adjustable resilient means for actuating said pawl, means operative upon reciprocation of the cross head for tensioning said resilient means, and 25 means for turning said turret in the reverse direction.

8. In a heel nailing machine having a reciprocating cross head, in combination, an oscillatable turret, a ratchet fast thereto, a

lever pivoted upon the cross head, a pawl 30 mounted upon one end of the lever and arranged for engagement with said ratchet, a spring tending when under tension to swing said lever and thereby, through the pawl and ratchet, to turn the turret, and a fixed 35 member arranged, upon downward movement of the cross head, to contact with the opposite end of said lever and thereby to tension the spring.

9. In a heel nailing machine having a reciprocating cross head, a turret rotatable thereon, a ratchet fast to the turret, a lever pivoted to said cross head and provided with a pawl engageable with the ratchet, a coil 40 spring connected to said lever and tending 45 when under tension to swing said lever and thereby through said pawl and ratchet to turn the turret, a roll mounted upon a fixed support for engagement with the lever upon downward movement of the cross head to 50 thereby tension said spring, a cam carried by said pawl, and an adjustable stop carried by the cross head, contact of said cam and stop acting to disengage said pawl and ratchet. 55

In testimony whereof I have signed my name to this specification.

GEORGE M. PETTENGILL.
